UNITED STATES PATENT OFFICE.

FRED G. SHOUDY, OF ROCKFORD, ILLINOIS.

DESIGN FOR A GROCER'S CABINET.

SPECIFICATION forming part of Design No. 22,730, dated August 22, 1893.

Application filed April 24, 1893. Serial No. 471,700. Term of patent 7 years.

To all whom it may concern:

Be it known that I, FRED G. SHOUDY, a citizen of the United States, residing at Rockford, in the county of Winnebago and State 5 of Illinois, have invented and produced a new and original Design for a Grocer's Cabinet, of which the following is a specification, reference being had to the accompanying drawing.

10 The cabinet is composed of ends 1, each of which comprises a vertical rear piece 6 and inclined front piece 7, an upper cross-piece 8, a lower cross-piece 9 and panels 11. The ends are supported upon a bed-board 10 the edges 15 of which project outward from the end pieces and the front of the cabinet and are rounded. The bed-board is supported by legs 5. 2 de-

notes an ornamental cornice on the top of the cabinet, and 3 denotes partitions to receive drawers 4.

The leading features of the design are the ends composed of the vertical rear pieces, the inclined front pieces, the panels, the ornamental cornice and the bed-board having its edges projecting outwardly beyond the cabinet and rounded.

20 What I claim is—

A design for a grocer's cabinet herein shown and described.

FRED G. SHOUDY.
